[57] **CLAIM**

The ornamental design for an enclosure for an electronic thermostat or the like, substantially as shown and described.

DESCRIPTION

FIG. 1 is a front perspective view of an enclosure for an electronic thermostat or the like showing my new design;

FIG. 2 is a top plan view thereof;

FIG. 3 is a front elevational view thereof;

FIG. 4 is a bottom plan view thereof; and

FIG. 5 is a left side elevational view thereof.

The rear is unornamented.
